UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

METHOD OF APPLYING BLACKING TO BOOTS OR SHOES.

1,285,111.

Specification of Letters Patent.

Patented Nov. 19, 1918.

Application filed December 17, 1917. Serial No. 207,494.

To all whom it may concern:

Be it known that I, FREDERICK M. FURBER, a citizen of the United States, residing at Revere, in the county of Suffolk and State 5 of Massachusetts, have invented certain Improvements in Methods of Applying Blacking to Boots or Shoes, of which the following description, in connection with the accompanying drawings, is a specification, like 10 reference characters on the drawings indicating like parts in the several figures.

This invention relates to a method of applying blacking to boots and shoes and, although it is in no respect so limited, it finds 15 particular application to the blacking of heels with quick drying blacking. For convenience of discussion, the term "blacking" will be used frequently in the specification and claims to include all sorts of similar finishing material, such as inks, colored stains, enamel of any desired color, etc., and the work will be referred to as the "heel" although the invention obviously has application to other parts of a boot or shoe.

25 Certain kinds of finish, of which white enamel is a notable example, have the characteristic of drying very quickly. Partly for this reason and partly perhaps because they are composed largely of varnish, considerable difficulty is experienced in applying this blacking without leaving the marks 30 of the bristles of the applying brush or of overlapping brush strokes. It has been customary, accordingly, to apply manually blackings of this sort with a single relative movement of the shoe and a soft camel's hair brush. This operation, because of the 35 necessity of getting the blacking into the rand crease without smoothing the upper, is obviously slow and expensive and great difficulty has been experienced in thereby thoroughly applying the blacking to the rand crease at the time that it is applied to the 40 surface of the heel. Because of the quick drying quality of this class of blacking, it has been found inexpedient to make more than one application of blacking to the heel for the reason that overlapping strokes leave a noticeable ridge. Furthermore, any attempt to utilize the ordinary type of blacking machine having driven brushes with 45 moderately stiff bristles almost invariably

results in the production of brush marks. An object of the invention is to devise a method of blacking heels by means of which 55 blacking may be successfully applied and the above mentioned and other difficulties avoided.

According to the preferred practice of the invention, the blacking is first applied to 60 the rand crease and an adjacent portion of the heel by a single relative movement of the work and a blacking applying means designed to furnish blacking to and open up the rand crease and preferably to a narrow 65 portion of the surface of the heel or edge of the sole immediately adjacent thereto. Blacking is then applied to the remainder of the surface of the heel in any desired manner as, for example, by a single stroke of 70 a soft camel's hair brush around the periphery of the heel. This latter step of the operation can now be practised expeditiously because it is no longer necessary to get into the rand crease or to the extreme top edge 75 of the heel. If this operation results in the production of a ridge due to overlapping brush strokes, such a ridge may be effaced, for example, by beading the heel along its upper edge at the point where the overlap- 80 ping strokes occurred.

The first step of this operation may preferably be effected by utilizing the machine which forms the subject-matter of my co-pending application Serial No. 202,143 filed 85 November 15, 1917. A feature of the invention consists in rotating a blacking applying member in engagement with the rand crease in order to insure the thorough application of blacking to the crease and thereby sub- 90 stantially simultaneously to open said crease and beat down the upper surface of the sole or heel, and in applying blacking to a portion of the face of the heel or edge of the sole by means of a single movement relatively to 95 a stationary member in order to avoid brush marks or the like such as might result from a plurality of strokes.

This and other features of the invention will be more readily understood from a consideration of the following specification taken in connection with the accompanying drawings, in which,—

Figure 1 is a plan view of a machine by

means of which the first step of my novel method may be conveniently carried out;

Fig. 2 shows the application of a shoe to this machine in order to carry out the first 5 step of the method;

Fig. 3 shows how the second step of the method may be carried out; and

Fig. 4 illustrates the completion of the operation.

- 10 One form of machine by means of which the first step of my novel method may be carried out is illustrated in Fig. 1 and will be seen to comprise a main power shaft 10 connected by worm gears to a jack shaft 12 connected by worm gears to a jack shaft 12 15 supporting a disk 14 which dips in blacking contained in a tank 16 and which delivers the same to one face of the concave disk constituting the rand crease guide 20. This guide 20 is positively driven by means of a 20 gear connection to the shaft 12 and is arranged to rotate in a counter-clockwise direction as viewed from the concave side of the disk. The convex side of the disk is cleaned by means of a wiper 22 of usual 25 form so that no blacking will be applied to the upper of the shoe when the disk is inserted in the rand crease.

Mounted beside the disk and in frictional engagement with a portion of the periphery thereof is a soft bristle brush 24 whose shaft 26 is supported in a bracket 28 adjustably held upon the frame by means of a bolt 30. The upper end of the bracket is slotted at 32 to allow backward and forward adjustment 35 of the bracket and its brush shaft 26, this movement being restricted to a straight line by co-acting faces 29 on the bracket and the frame, and the shaft 26 may be longitudinally adjusted within the bracket by loosening a set screw passing through a collar 32' between two arms of the lower end of the bracket. Upon this collar are ratchet teeth 34 which co-operate with a pawl 36 upon the bracket. As will be seen by an inspection 40 of the drawing the brush is undriven and is arranged for free rotation in the same direction as the disk but is held stationary upon the application of the work which is commonly moved upwardly against 45 the motion of the disk.

The preferred method of blacking a heel in accordance with my invention is to apply blacking to the rand crease 40 and a portion of the adjacent face of the heel 42 or edge 50 of the sole in one operation, as indicated in Fig. 2, and to black the remainder of the heel in another operation, as indicated in Fig. 3. The term "rand crease" is used generically herein to indicate any part of the 55 crease between the upper and the sole. Any indications of a joint between the two applications of blacking may then be effaced, for example, by beading the upper edge of the heel in the usual manner, as for example, 60 by means of a beading wheel 60 such as

shown in Fig. 4. In practising this method upon the improved machine just described, the work will first be held in the position indicated in Fig. 2 and will then be moved upwardly past the relatively stationary 70 brush and the disk against the direction of rotation of the disk and, being turned, blacking will be applied to the rand crease of the shoe and a portion of the face of the heel or edge of the sole adjacent thereto with a 75 single relative movement of the work and the machine. The rotation of the rand crease guide disk 20 in the rand crease will not only apply the blacking to the crease but will at the same time open up the crease, 80 where it may have become partially closed during the operation of heel trimming or heel scouring and will also beat down the upper edge of the sole or heel and eliminate any rough edges or loose fibers. After an 85 application of the work to the machine, the brush will be carried forward in a counter-clockwise direction by reason of the frictional engagement between the guide 20 and the brush and blacking will be delivered to 90 that portion of the brush which is advancing into position for engagement with the work, it being somewhat retarded by the brush and piled up, thereby to fill the brush.

The remainder of the face of the heel may 95 then be blacked, according to the second step of my method, in any desired fashion as, for example, by the manual application of blacking with a single stroke of a camel's hair brush 50 (see Fig. 3). Inasmuch as 100 the upper edge of the face of the heel has already been blacked it is no longer essential that this manual operation be carried over the extreme width of the heel and consequently it may be effected much more 105 quickly and accurately. Any possible ridge (see Fig. 3) which may be formed by the overlapping strokes of the two applications of blacking will, according to the third step of my method, be effaced when the heel is 110 beaded in the usual manner by means of a wheel 60 such as shown in Fig. 4.

Having thus described my invention, what I claim as new and desire to secure by Letters Patent is:

1. The method of blacking a heel which consists in applying blacking to a portion of the face of the heel or edge of the sole adjacent to the upper in one operation, applying blacking to the remainder of the face 120 of the heel in another operation, and effacing any indications of the joint between the two applications.

2. The method of blacking a heel which consists in opening up and applying blacking to the rand crease in one operation, and applying blacking to the face of the heel in another operation.

3. The method of blacking a heel which consists in applying blacking to the upper 130

portion of the face of the heel or edge of the sole and beating the upper edge of the sole or heel in one operation, applying blacking to the remainder of the heel in another operation, and beading the heel along the joint between the two applications to efface any indications of a joint.

4. The method of blacking a heel which consists in opening up and applying a coat of blacking to the rand crease and adjacent edge of the heel or sole in one operation, and applying a coat of blacking to the remainder of the heel in another operation so that it slightly overlaps the coat applied to the top edge of the heel or sole.

5. The method of blacking a heel which consists in applying a coat of blacking to the rand crease and adjacent edge of the heel or sole and beating the upper edge of the sole or heel in one operation, applying a coat of blacking to the remainder of the heel in another operation so that it slightly overlaps the coat applied to the top edge of the heel or sole, and effacing the marks of overlapping by beading said top edge of the heel or sole.

6. The method of blacking a heel which consists in applying blacking to the rand crease and adjacent edge of the sole or heel by moving the work along a guide and against a relatively stationary blacking applying member, and applying blacking to

the remainder of the face of the heel by holding the work relatively stationary and drawing a blacking applying device around the surface of the heel.

7. The method of blacking a heel which consists in applying blacking to the rand crease and adjacent edge of the sole or heel by moving the work along a guide and against a relatively stationary blacking applying member, applying blacking to the remainder of the face of the heel by holding the work relatively stationary and drawing a blacking device around the surface of the heel and effacing any indications of the joint between the two applications of blacking by beading the top edge of the heel or sole.

8. The method of blacking a heel which consists in rotating a blacking applying member in engagement with the rand crease to insure the thorough application of blacking to the crease, applying blacking to a portion of the face of the heel or edge of the sole by means of a single movement relatively to a stationary member so that there will be no brush streaks as from a plurality of strokes, and applying blacking to the remainder of the face of the heel in an operation separate from said first-named applications.

In testimony whereof I have signed my name to this specification.

FREDERICK M. FURBER.

Correction in Letters Patent No. 1,285,111.

It is hereby certified that in Letters Patent No. 1,285,111, granted November 19, 1918, upon the application of Frederick M. Furber, of Revere, Massachusetts, for an improvement in "Methods of Applying Blacking to Boots or Shoes," an error appears in the printed specification requiring correction as follows: Page 1, line 39, for the word "smoothing" read *smooching*; and that the said Letters Patent should be read with this correction therein that the same may conform to the record of the case in the Patent Office.

Signed and sealed this 11th day of November, A. D., 1919.

[SEAL.]

M. H. COULSON,

Acting Commissioner of Patents.

Cl. 12—142.
